UNITED STATES PATENT OFFICE.

CHARLES S. RYERSON, OF DETROIT, MICHIGAN.

APPARATUS FOR BENDING PIPES.

1,240,605.

Specification of Letters Patent. Patented Sept. 18, 1917.

Application filed March 28, 1917. Serial No. 157,877.

To all whom it may concern:

Be it known that I, CHARLES S. RYERSON, a citizen of the United States, residing at Detroit, county of Wayne, State of Michigan, have invented a certain new and useful Improvement in Apparatus for Bending Pipes, and declare the following to be a full, clear, and exact description of the same, such as will enable others skilled in the art to which it pertains to make and use the same, reference being had to the accompanying drawings, which form a part of this specification.

This invention relates to apparatus for bending pipes, or tubing, and has for its object an improved construction embodying comparatively few parts and easily portable, whereby such bending may be accomplished easily and efficiently.

20 In the drawings:

Figure I is a side elevation of my improved device, with a section of pipe shown in position therein.

Fig. II is an end elevational view, the pipe being shown in position therein.

Fig. III is an end elevation, partly in section, of the frame of the device alone.

Fig. IV is a fragmentary plan view of the end of the frame from which the floor has been cut away to permit the swing of the pipe bending member.

Fig. V is a side elevation of the pipe-engaging segment removed from the frame.

Fig. VI is an end view of this segment.

Fig. VII is a sectional view of the pipe-engaging segment, along the line $\alpha-\alpha$, of Fig. V.

Fig. VIII is a side elevational view of a modified form of segment member, adapted especially for handling the ends of threaded pipe or bends with an especially short radius.

Fig. IX is an end view of this modified form of segment.

45 A represents a board or other suitable base, to which is fixed, by screws or otherwise, the bed-plate B of the frame C, between whose constituent side pieces, extends a central open space, in which are slidably journalled, underneath the inturned top edges D of the frame, the trunnions E of the pipe-engaging segment member F. As shown in Fig. IV, the floor or bed-plate B of the frame is preferably cut away somewhat as at B' to permit the lower end of the pipe-engaging segment member to swing

freely. This consists of a lower pipe jaw G, which is adapted to engage about half way around the inserted section of pipe H, which rests upon the floor or bed-plate B. 60 With the pipe in position through the jaw portion G of the segment, the several members occupy the position shown in Fig. I. Upon the manual actuation of the lever L, however, the spring-held dog K engages in 65 the teeth of the ratchet member M, tending to rotate the entire segment piece F about its trunnions E as a horizontally moving center, and consequently to roll more of the curved peripheral edge N of the segment 70 against the pipe H. This of course can only be brought about by the yielding of the pipe to the bending influence thus exerted, since its free end is held from swinging downwardly by the presence of the bed-plate of 75 the frame. The semi-circular jaw portion G, of course, holds the pipe firmly against yielding in the other direction, and the consequence is that the desired degree of curvature is imparted to the pipe, after which it 80 is easily removed. For relatively slight curvature, only a slight actuation of the lever L is required, and in fact I desire it clearly understood as within the scope of 85 my invention to have the actuating lever rigid with respect to the pipe-engaging segment, instead of journaled about its trunnion center, thus doing away, under some circumstances, as for example a slight degree of bending or a very soft pipe, with the 90 ratchet and dog members. But where an 80 or 90 degree curve is desired, several notches of the ratchet M may have to be successively engaged by the dog K. As the segment is 95 turned about its rotative axis, the overengaging top edges D of the frame hold the trunnion ends E down and yet permit them to slide along their under surface, lengthwise of the frame. The curved periphery N of the segment piece receives the pipe, as it 100 is bent theretoward, into its troughed portion, but the pipe is in no other way moved with respect to the frame C; in other words it is not "wiped" or drawn along the frame as the bending process goes on; on the contrary, the curved surface of the segment rolls onto and in contact with it, and since the guiding influence of the top edges of the trough N becomes effective as soon as the 105 bending process is begun, the pipe is held thereby, as well as by the gripping of the jaws G, against slipping out through the

open side of the jaw. The trough or peripheral groove N also serves to hold the pipe against lateral expansion and consequent flattening as it is being bent about the 5 segment's periphery.

In Figs. VIII and IX, I have shown a modified form of segment member in which the pipe-engaging portion consists of a completely inclosed circular portion R, instead 10 of the jaw G of the first type. It will be noted that in this form the curved peripheral edge of the segment is much smaller. This form of device is especially adapted 15 for handling the end of a pipe and for avoiding the mutilation of the threading frequently there present, and is adapted, because of its short periphery, to impart a bend of unusually small radius of the pipe thus near one end. The downwardly holding 20 influence of the overengaging frame edges D on the trunnion E is the same in each form, however.

What I claim is:—

1. In combination with an open-ended 25 frame member, whose side portions are provided with overengaging upper edges, a pressing segment having trunnion portions adapted to engage the under faces of said overengaging edges and to be movable 30 lengthwise thereof when the segment is rotatively actuated against an attached length of pipe interposed between its periphery and the floor of the frame member.

2. The combination of a frame member 35 adapted to support an inserted length of pipe, a segment member rotatable therewithin and with its axis of rotation movable lengthwise thereof in a line parallel to the axis of said pipe, and means for rotating 40 said segment, thereby drawing the pipe about the curved periphery of said segment.

3. In combination with a frame, a segment member provided with a pipe-engaging 45 projection adapted to engage a length of pipe inserted in said frame and to be peripherally rocked thereagainst, said seg-

ment member having laterally projecting trunnion portions adapted to slidably engage complementary overengaging portions 50 of the frame, whereby the axis of rotation of the segment, when it is rocked, is guided along a line parallel to the axis of the pipe.

4. In a device of the class described, the combination of a segment member adapted 55 to peripherally engage a pipe, means for rocking said segment member in a plane parallel to the axis of the pipe to draw the same thereabout, and a holding frame adapted to hold the segment in firm engagement 60 with the pipe while the rocking operation is in progress, the axis of rotation of said segment being longitudinally movable with respect to said frame.

5. In a device of the class described, in 65 combination with a segment member having a curved peripheral portion provided with a pipe-engaging projection at one end thereof and having laterally projecting trunnion portions, a frame member provided with 70 overengaging sides against the under faces of which said trunnion members slidably engage when the segment is rocked, thereby causing the same to move lengthwise thereof when rocked against a length of pipe inserted in said frame.

6. A pipe-bending tool, having, in combination with a pipe-holding portion at one end, a troughed peripheral portion extending therefrom to the other end, adapted to 80 confine a pipe bent thereabout against lateral expansion, means for rotating said tool, and a holding frame lengthwise of which the axis of rotation of said tool is adapted to move in a plane parallel with 85 the floor thereof, to draw a pipe rested on the floor of the frame member about the troughed peripheral portion of the tool.

In testimony whereof, I sign this specification in the presence of two witnesses.

CHARLES S. RYERSON.
